SPRAY NOZZLE

Edward J. Marshall, Cambridge, England, assignor to Arthur Kennedy Dorman, Cambridge, England

Application April 4, 1950, Serial No. 153,870
In Great Britain January 11, 1949

4 Claims. (Cl. 299—120)

1

The present invention relates to a spray nozzle. It may be used for example for the spraying of trees, crops or other objects with liquids for insecticidal control purposes or for applying coating compositions. The spray nozzle may also be used for spraying or cleansing cattle.

An object of the invention is to provide a nozzle which can be adjusted as desired to give a wide cone of fine spray or a concentrated jet, or a spray intermediate between these extremes.

According to one aspect of the invention a spray nozzle comprises a hollow outer member provided with an orifice, the internal surface of the member surrounding the orifice being of conical form, and an inner member, which has a coned end, and which is movable relatively towards and away from and substantially in axial alignment with the orifice, one or more grooves, orifices, or passages leading to the orifice and extending at an angle to the axis thereof, being provided in at least one of the members to produce a fine spray when the coned end of the inner member makes contact with said conical internal surface. For this purpose, the inner member may be provided with one or more grooves along its coned surface. Alternatively, the grooves may be replaced by one or more holes formed adjacent to the coned end and extending inwardly to the end of the inner member.

When the coned end of the inner member is close to or in contact with the coned surface of the outer member, a fine widely dispersed spray is produced, most or all of the liquid passing through the grooves or passages which are provided according to the invention. When the coned surfaces of the inner and outer members are widely separated, a concentrated jet is produced. Intermediate positions of adjustment give sprays with intermediate spread.

According to a feature of the invention the grooves or passages are preferably so arranged that they form tangents to a cylinder coaxial with the nozzle so that a swirl is imparted to the liquid passing through them.

According to a further feature the angle of the coned end of the inner member is preferably made similar or equal to that of the angle of the coned surface surrounding the discharge orifice to enable a close fit to be obtained between these surfaces.

According to another aspect of the invention a spray nozzle comprises a hollow outer member provided with an axial discharge orifice and with a conical internal surface surrounding the orifice, a hollow inner member which has a conical

end and an axial passage open at the other end for connection to a supply of liquid under pressure, is movable relatively towards and away from and substantially in axial alignment with the orifice to act as a valve in co-operation with said conical surface, and has apertures to connect said interior passage with a surrounding enclosed space in communication with the discharge orifice when the said valve is open, the nozzle also comprising means permitting relative axial movement between said inner and outer members and a packing to inhibit leakage through said means, and one or more grooves, orifices, or passages leading to the discharge orifice and extending at an angle to the axis thereof, being provided in at least one of the members to produce a fine spray when the coned end of the inner member makes contact with said conical internal surface. Advantageously the spray-producing grooves or passages are formed in the inner member.

The accompanying drawing is an axial section of one form of nozzle incorporating the invention. The nozzle is formed of three main parts, a base member 10 having a screw thread 11 for attachment to a supply pipe, a hollow inner member 12 having an externally screw-threaded extension 14 for engagement with a female thread provided in an axial bore 15 of the base member 10, and a hollow outer member 16 having internal screw threads 17, co-operating with an external thread on the base member 10 to provide adjustment in an axial direction between the inner and outer member 12 and 16. The inner member 12 has its end formed as a truncated cone 18. Between the coned end 18 and the screw thread by which it is mounted, the inner member has a hexagonal flange 19 adapted for engagement by a spanner. The corners of this flange are rounded for guiding co-operation with the bore 23, which forms the main cavity of the outer member 16. In order to supply liquid to the interior of the outer member 16, radial bores 20 extend from the middle of each hexagon side to an axial bore 13 of the inner member. The bore 13 is open to the bore 15 of the base member to which liquid is supplied. The leading end of the inner member 12 is flattened as shown at 21, and a number of spray-producing passages are formed by bores 22 extending from the flat end surface 21 to the bore 13 of the inner member. These bores are spaced from and oblique to the axis of the nozzle so as to impart a swirl to the spray produced by them. In order to inhibit leakage between the base and the outer member in any

position of adjustment, a packing gasket 24 of rubber or similar material in the form of a cup with a tapered edge co-operates with the bore 23 of the outer member 16. Its flat portion is clamped between the opposed ends of the inner and base members. The outer member has a delivery orifice 25 on the axis of the nozzle, the orifice being extended inwardly by an internal conical surface 27 which is of the same angle as the cone surface 18 on the end of the inner member 12. The outer portion 26 of the delivery orifice may be chamfered as shown.

When the outer member 16 is turned to cause the inner and outer members to move towards each other, the coned portion 18 of the inner member 12 enters the coned seat 27 at the delivery orifice 25. In the extreme position, the coned surfaces 18 and 27 meet, leaving only the bores 22 to carry liquid to the orifice 25, resulting in the formation of a fine spray. As the outer member 16 is unscrewed to increase the separation of the coned surfaces, the volume and concentration of the spray are increased progressively until a solid jet is delivered.

The embodiment herein described and illustrated may be modified in various respects. For example the passages 22, which extend through the body of the valve element, may be replaced or supplemented by grooves formed in one or both of the co-operating cone surfaces 18 and 27. It is also to be understood that the invention is not limited to the use of a screw to control the axial relative movement of the inner and outer members and that other equivalent means may be provided for this purpose. The outer member may if desired be made as a sleeve which is adjustable in an axial direction, the position of the sleeve being controlled manually, or locking means may be provided for this purpose.

I claim:

1. An adjustable nozzle for spraying liquids comprising a hollow outer member and an inner member adapted to be located within the outer member, a liquid outlet orifice in said hollow outer member, a conical interior surface to said outer member communicating with said liquid

outlet orifice, a conical seating surface on the exterior of said inner member, means for axially adjusting the relative positions of said outer and inner members from a position in which the conical exterior surface of said inner member seats in valve-like fashion upon the conical interior surface of said outer member to a position in which the two conical surfaces are separated by an appreciable gap, an axial bore in said inner member adapted for communication with a source of liquid supply, a plurality of radial passages extending from said bore to the exterior of said inner member, and at least one passage extending at an angle from said bore and leading towards the orifice in said outer member so that when the inner member seats on the conical valve seating afforded by the interior conical portion of the outer member, liquid may pass up the angularly-extending passages to produce a fine spray from the outlet orifice and when the inner member is axially displaced from said seating, liquid may pass along the radial passages and be discharged from the outlet orifice in a solid jet.

2. A nozzle as claimed in claim 1, in which the passages extending angularly from said axial bore extend to the conical surface of the inner member near the axis thereof.

3. A nozzle as claimed in claim 1, in which the angularly-extending passages are spaced from and oblique to the axis of the nozzle so as to impart a swirl to the spray produced by them.

4. A nozzle as claimed in claim 2, in which the angularly-extending passages are spaced from and oblique to the axis of the nozzle so as to impart a swirl to the spray produced by them.

EDWARD J. MARSHALL.
